UNITED STATES PATENT OFFICE.

ERNEST A. GROSS, OF LAMOILLE, MINNESOTA.

ARMAMENT.

Application filed April 1, 1926. Serial No. 99,151.

This invention relates to improvements in armament constructions.

The primary object of the invention is the provision of a bullet-proof collapsible cabinet construction which may be used in connection with vehicles, such as trucks, being of a nature for detachable connection thereon wherein an armed guard may be safely positioned for the guarding of money, or other valuables which are being transported from place to place.

A further object of this invention is the provision of armament for vehicles used in the transporting of valuables, preferably embodying a bullet-proof steel cabinet construction such as set forth in my Patent #1,453,792, patented May 1, 1923, and embodying the specific improvements thereover in rendering the bullet-proof cabinet susceptible of compact attachment upon a truck.

A further object of this invention is the provision of an improved collapsible bullet-proof steel cabinet construction adapted for use upon motor vehicles, and embodying portable means to place the same in detachable relation on the vehicle in such relation that the same may receive an armed guard with valuables in a protected and secured relation.

A further object of this invention is the provision of an improved bullet-proof cabinet construction having improved guarded ports and a door which is controlled from the inside for facilitating passage of valuables to and from the cabinet.

Other objects and advantages of this invention will be apparent during the course of the following detailed description.

In the drawings, forming a part of this specification, and wherein similar reference characters designate corresponding parts throughout the several views,

Figure 1 is a side elevation of a motor truck having the improved armament cabinet installed thereon in an extended relation, and showing in dotted lines the collapsed portable position of the armament on the platform of a truck.

Figure 2 is a longitudinal sectional view taken through the bullet-proof armament cabinet in extended relation upon the truck.

Figure 3 is a cross sectional view showing the collapsed position of parts of the armament on the truck.

Figures 4 and 5 are cross sectional views

taken substantially on their respective lines in Figures 2 and 3 of the drawings.

Figure 6 is a side elevation of the collapsed bullet-proof steel cabinet, showing features of construction thereof.

Figure 7 is an elevation of the entrance end of the cabinet.

Figure 8 is an enlarged sectional view taken substantially on the line 8—8 of Figure 7.

Figure 9 is a view from the inside of the cabinet at the port opening thereof, taken substantially in the direction indicated in Figure 8.

Figure 10 is a fragmentary view, illustrating the portable wheels and the means to hold the collapsible portions of the cabinet in a collapsed relation.

In the drawings, wherein for the purpose of illustration is shown only a preferred embodiment of the invention, the letter A may generally designate the improved bullet-proof cabinet, which is of a nature for detachable connection upon a motor truck B.

The motor truck B is of course of any approved formation, and the same may comprise a driver's compartment or cab construction 10, which has a rear wall 11 with an opening 12 therethrough which may be covered by a transparent pane, if desired. The truck B is provided with a floor or platform 14, and a principal feature of the invention is the compact attachment of the armament cabinet A against the rear wall 11 of the cab 10, at the forward portion of the platform 14 only, so that the rear portion of the platform, as illustrated in Figure 1 is unobstructed for loading of articles or material thereon.

The cabinet A in the main follows the construction of my patent above referred to and comprises a rigid box-like section C and a collapsible section D cooperatively related with the rigid section C.

The rigid section C of the cabinet is formed of steel plate material, of a bullet-proof nature, and comprises the wall 20, bottom wall 21; top wall 22; and side walls 23 and 24. The walls 20 to 24 inclusive are integrally formed, and arranged in rectangular formation, the rigid section C being open at the rear thereof and over which the collapsible section D is adapted to cooperate in providing the bullet-proof cabinet, as can readily be understood.

The front wall 20 of the rigid section C

is preferably provided with a sight opening 26 therein, which when the cabinet A is in position will align with the window opening 12 in the rear wall of the cab construction, as is illustrated in Figure 2 of the drawings, and thus permit the guard in the interior of compartment 30 of the cabinet A to have a line of sight forwardly of the vehicle in the direction in which the same 10 is being propelled.

The sight opening 26, of course, is to be guarded, and to this end a steel closure 31 is provided, as is illustrated in Figure 4 of the drawings, pivoted at 32 on the front 15 wall 20, preferably at one of the upper corners of the sight opening 26; the door 31 being of the gravity operated type to come to rest upon a bracket 33 which is flanged inwardly to provide a socket 34 wherein the 20 lower margin of the door 31 is received in order to lock the same in position and to prevent the same from being pressed inwardly by force exerted exteriorly of the cabinet A, and as can readily be understood 25 from Figures 2 and 4 of the drawings. A handle projection 35 may be provided at the top of the closure at its free swinging end, to facilitate lifting thereof.

The collapsible section D comprises top 30 and bottom walls 40 and 41 respectively, which are hingedly connected at 42 and 43 respectively to the top and bottom walls 22 and 21 of the rigid section C, to swing into the pocket of the rigid section C, as illustrated in Figure 3 when the top and bottom walls of the collapsible section are collapsed, as illustrated in Figure 3. The section D also includes side walls 44 and 45 which are respectively hinged to the side 35 walls 23 and 24 of the rigid section, by hinges 46 which swing inwardly to permit the side wall 45 to be swung inwardly first, towards the open rear of the rigid compartment C, and then the side wall 44 to be 40 swung thereover.

The collapsible section D furthermore includes a rear wall or closure 50 hingedly connected at 51 to the rearmost edge of the collapsible side wall 44, in such relation that 45 the door or closure 50 may be swung outwardly into a parallel plane with the wall 44 into a collapsed relation as illustrated in Figure 3.

The walls 41, 42, 43, 44 and 50 have inter- 50 fitting parts to overlap at the abutting margins thereof, to provide a closed cabinet with efficient connections when the same is extended, as is illustrated in several of the drawings, and as is set forth in my patent 55 above referred to.

An important feature in connection with the construction of the collapsible cabinet section D is the provision of an article inserting and removing opening 60 in the 60 lower portion of the door or closure 50,

through which money, currency, or other valuables may be passed to the guard within the compartment 30, or from the guard exteriorly of the cabinet, without the necessity of opening the cabinet and thus impairing the efficiency of its use, in that bandits could then reach the guard and the valuables as well. At the inside surface of the closure 50 it is preferred to place a vertical sliding door 62 having the edges thereof 70 slidably received in side grooves provided by flanged brackets 63 attached to the inside surface of the door 50; the lower portion of the closure 62 being received in a flanged bracket 64 attached to the door 50, to limit the downward and closed position of the door 62 as is illustrated in Figure 2 of the drawings. In the door 50 is also placed a port opening 65 smaller than the opening 60, about the middle of the height of the door 50, which is shut by a slideable closure 66 operable at the inside of the door 50, and retained by means of flanged brackets similar to the door 62 above described. Also, at the top of the door 50 it is preferred to provide a sight hole 67, with an enlarged bevel edge at the rear of the door 50, through which the guard may observe happenings exteriorly of the cabinet. Normally the opening 67 is closed by a door 68 inside of the door 50 and controlled therefrom. A pair of the port openings 65 may be provided, as well as a pair of the sight openings 67 in the rear wall or door 50, in the relation illustrated in Figure 7.

As is illustrated in Figure 4 of the drawings it is preferred to provide sight openings in the rigid section C, similar to the sight openings 67 above described, over which slideable closures 70 are operable from the inside of the compartment 30. Similarly, at each side of the closure 31 it is preferred to provide port openings in the wall 20, normally closed by means of vertical slides 72 operable from the inside of the compartment 30. These port openings and sight openings which are controlled by the closures 70 and 72 are normally not used except when the armament cabinet is off the truck, and used for guarding a paymaster, or in like instance.

The side walls of both the rigid and collapsible sections D and D may also be provided with upper bevel sight openings controlled by inside closures 75, and lower port openings may also be provided controlled by inside closures 76, as is illustrated in the drawings.

An important feature of the invention is the provision of stop lugs 77 and 78 extending inwardly from each of the side walls 23 and 24 of the rigid section C, to engage the free swinging edges of the top and bottom walls 40 and 41 of the collapsible section D when the said walls 40 and 41 are 125

collapsed inwardly into the pockets of the rigid section C whereby to limit the amplitude of movement of the free swinging edges of the walls 40 and 41 towards the wall 20, 5 to provide a space between the collapsed walls of the collapsible section D and the wall 20 of the rigid section C, wherein defensive apparatus, such as revolvers, guns, ammunition, and other mechanism may be placed. This may be carried in an enclosed 10 relation even when the cabinet is collapsed as illustrated in Figure 3.

Novel means is provided for attaching the cabinet A to the truck comprising a pair of 15 eye bolts 80 rigidly secured on the wall 11 of the cab 10, adapted to extend thru apertures 81 in the wall 20 of the rigid section C so that the eyes of the bolts 80 extend into the compartment 30, where the guard therein 20 may insert short wedges 82 in order to secure the walls 11 and 20 in abutting secured relation to support the cabinet A in a vertical position rigid with the cab 10.

Preliminary attaching means such as eye 25 bolts and a hasp carried by the rear wall of the cab and the rigid section of the cabinet A may be provided to temporarily secure the cabinet A in vertical position to the cab prior to extending the collapsible walls of 30 the section D into place, to permit the secure and rigid attachment of the cabinet A by the eye bolts 80 and wedges 82 above mentioned. Such construction may comprise hasps 85 carried by the rigid section C, as illustrated in Figure 4, adapted to receive eye bolts 86 carried by the cab wall 11 secured in place by cotter pins 89, or the like, in the relation mentioned.

The cabinet A must be transported to and 40 from the truck B, and thus be portable from place to place to serve different uses. To this it is preferred to provide caster wheels or rollers 90 secured by means of brackets 91 to the lower ends of the side walls 23 and 45 24 of the rigid section C; the brackets 91 being positioned in right angled relation with respect to the length of the walls 23 and 24, and supporting the rollers 90 at the free ends thereof in a relation spaced above 50 the plane of the bottom wall 21 of the rigid section C. This places the rollers 90 and the brackets 91 in a spaced relation above the supporting floor of the truck when the cabinet A is vertically positioned either in extended or collapsed relation, and this 55 obviates the necessity of detaching the caster wheels from the lower end of the cabinet. The brackets 91 are of such length that the outer ends of the rollers 90 extend beyond 60 the rearmost edge of the door 50 when the cabinet section D is collapsed. Thus upon tipping of the collapsed cabinet section A the rollers 90 will engage the floor or ground surface as illustrated in Figure 1 of the

drawings to permit the cabinet A being propelled. 65

Brackets 92 are also attached to the side walls 23 and 24 of the rigid cabinet section C, about midway of the ends of said walls, and the bracket 92 has portions thereof extending in right angled relation to the height of the cabinet, and therein stub shafts 93 rotatably bear. Keyed to these stub shafts 93 are relatively large supporting wheels 94, at opposite sides of the cabinet adjacent the 70 walls 23 and 24, the wheels 94 being of a diameter so that the segmental portion thereof projects beyond the plane of the rear edge of the wall 50 when the cabinet section D is collapsed, in order to permit the support of the cabinet A upon the rollers 90 and the wheels 94 to facilitate its being propelled, 75 much in the same manner as a conventional hand truck.

In order to prevent displacement of the 80 collapsed walls of the section D, during the propelling of the cabinet A, it is preferred to provide detachable stop pins or projections 100, detachably insertable in the outer 85 ends of the brackets 92, in an extending relation across the rear of the rearmost wall 50, when the section D is collapsed, in the relation illustrated in Figure 10 of the drawings, to prevent the falling apart of the collapsed walls of the section D, as is quite obvious. If desired, the brackets 92 may be detachable from the walls of the rigid section D, in order to remove the large 90 wheels 94 after the cabinet is installed in vertical guarding position. 95

From the foregoing description of this invention it is apparent that a novel armament cabinet has been provided, formed of armor plate or bullet-proof metal, which embodies features which renders the same compact in formation and particularly desirable for use in connection with the transportation of moneys, or other valuables; the same furnishing a bullet-proof and safety compartment for a guard to which bandits, robbers, and highwaymen do not have any access or means of harming the guard. 100

Various changes in the shape, size, and arrangement of parts may be made to the 105 form of invention herein shown and described, without departing from the spirit of this invention or the scope of the claims. 110

I claim:

1. An armor plate cabinet comprising a 120 rigid section having a front wall, rigid side walls, and rigid top and bottom walls formed to provide a pocket open at the rear thereof, said front wall having an opening upwardly therein to provide a sight opening, closure means for the sight opening operable from within the pocket of the rigid section, and a collapsible section at the open 125 part of said pocket of the rigid section com-

prising a plurality of movably connected top and bottom, side and rear walls, the rear wall having an article inserting and extracting opening therethrough, and a closure operable from within the compartment of the cabinet for the article opening in the rear wall of the collapsible section.

2. An armor plate cabinet comprising a rigid section having a front wall, rigid side walls, rigid top and bottom walls formed to provide a pocket open at the rear thereof, said front wall having an opening upwardly therein to provide a sight opening, closure means for the opening operable from within the pocket of the rigid section, and a collapsible section at the open part of the pocket of the rigid section comprising a plurality of movably connected top and bottom, side and rear walls, the rear wall having an article inserting and extracting opening therethrough, a closure operable from within the compartment of the cabinet for the article opening in the rear wall of the collapsible section, the walls of the rigid and collapsible sections having ports and sight openings therein, and closures operable over the last mentioned openings at the inside surfaces of said walls facing the compartment.

3. In combination with a vehicle having a supporting wall, eye bolts carried by the supporting wall, and an armor plate cabinet having a compartment therein and including a wall having openings for receiving the eye bolts of the supporting wall so that the eyes of the eye bolts project into said compartment, and wedges inserted through the eyes of the eye bolts and against the wall of the cabinet to hold the cabinet in supported relation with the wall which supports the eye bolts.

4. In combination with a vehicle having a supporting wall, eye bolts carried by the supporting wall, an armor plate cabinet having a compartment therein and including a wall having openings for receiving the eye bolts of the supporting wall so that the eyes of the eye bolts project into said compartment, wedges inserted through the eyes of the eye bolts and against the wall of the cabinet to hold the cabinet in supported relation with the wall which supports the eye bolts, said supporting wall having a sight opening therein and the adjacent wall of the cabinet having an opening therein adapted to align with the opening of the supporting wall.

5. In combination with a vehicle having a supporting wall, eye bolts carried by the supporting wall, an armor plate cabinet having a compartment therein and including a wall having openings for receiving the eye bolts of the supporting wall so that the eyes of the eye bolts project into said compartment,

wedges inserted through the eyes of the eye bolts and against the wall of the cabinet to hold the cabinet in supported relation with the wall which supports the eye bolts, said supporting wall having a sight opening therein and the adjacent wall of the cabinet having an opening therein adapted to align with the opening of the supporting wall, and a door for the opening of the cabinet wall operable within the compartment of the cabinet only to control the opening of the cabinet wall.

6. In armament the combination with a vehicle including an upstanding supporting wall having eye bolts thereon, a bullet-proof cabinet having a guard compartment therein, and means formed with the bullet-proof cabinet for connection to said eye bolts to hold the cabinet against said supporting wall.

7. In armament the combination with a vehicle including an upstanding supporting wall having eye bolts thereon, a bullet-proof cabinet having a guard compartment therein, and means formed with the bullet-proof cabinet for connection to said eye bolts to hold the cabinet against said supporting wall, said cabinet comprising a rigid section next to the supporting wall and an outer collapsible section including a rear wall having an opening therethrough.

8. In armament the combination with a vehicle including an upstanding supporting wall having eye bolts thereon, a bullet-proof cabinet having a guard compartment therein, means formed with the bullet-proof cabinet for connection to said eye bolts to hold the cabinet against said supporting wall, said cabinet comprising a rigid section next to the supporting wall and an outer collapsible section including a rear wall having an opening therethrough, and closure means operable from within the compartment of the cabinet for controlling said last mentioned opening.

9. In a portable bullet-proof cabinet the combination of a cabinet having metal plate bullet-proof walls, roller supporting means at one end of the cabinet, and large wheel supporting means intermediate the ends of the cabinet, said cabinet being formed to permit the roller means and large wheel means to extend beyond a vertical surface of the cabinet to permit its transportation when tipped.

10. In an armor plate cabinet of the class described the combination of a collapsible cabinet construction including a construction formed with the collapsible cabinet construction providing side walls, brackets on the lower ends of the side walls extending transversely of the collapsible cabinet construction and supporting rollers at the free ends thereof beyond the outer surfaces

- of the collapsible cabinet construction when collapsed, and large supporting wheels supported intermediate the ends of the cabinet upon the rigid walls and projecting beyond the outer surfaces of the collapsible cabinet construction when collapsed.
11. In a steel plate bullet-proof cabinet the combination of a box-like rigid section including top and bottom walls, side walls, and a front wall connected to provide a pocket open at the rear, a collapsible section movably connected with the rigid section at the rear thereof including wall portions which may be collapsed upon the rigid section or extended therefrom to provide an enclosed compartment of said cabinet sections, brackets rigidly connected at the lower ends of the side walls of the rigid section extending transversely therefrom above the plane of the bottom wall of the rigid section, rollers supported at the outer ends of said brackets in such relation that when the walls of the collapsible section are collapsed, said rollers will be extended beyond the rearmost surface of the rearmost wall of the collapsible sections so that upon being tipped the rollers may engage the ground surface for transporting the cabinet with the collapsible section collapsed.
12. In a steel plate bullet-proof cabinet the combination of a box-like rigid section including top and bottom walls, side walls, and a front wall connected to provide a pocket open at the rear, a collapsible section movably connected with the rigid section at the rear thereof including wall portions which may be collapsed upon the rigid section or extended therefrom to provide an enclosed compartment of said cabinet sections, brackets rigidly connected at the lower ends of the side walls of the rigid section extending transversely therefrom above the plane of the bottom wall of the rigid section, rollers supported at the outer ends of said brackets in such relation that when the walls of the collapsible section are collapsed, said rollers will be extended beyond the rearmost surface of the rearmost wall of the collapsible sections so that upon being tipped the rollers may engage the ground surface for transporting the cabinet with the collapsible section collapsed.
13. In a steel plate bullet-proof cabinet the combination of a box-like rigid section including top and bottom walls, side walls, and a front wall connected to provide a pocket open at the rear, a collapsible section movably connected with the rigid section at the rear thereof including wall portions which may be collapsed upon the rigid section or extended therefrom to provide an enclosed compartment of said cabinet sections, brackets rigidly connected at the lower ends of the side walls of the rigid section extending transversely therefrom above the plane of the bottom wall of the rigid section, rollers supported at the outer ends of said brackets in such relation that when the walls of the collapsible section are collapsed, said rollers will be extended beyond the rearmost surface of the rearmost wall of the collapsible sections so that upon being tipped the rollers may engage the ground surface for transporting the cabinet with the collapsible section collapsed, brackets rigidly connected with the side walls of the rigid section intermediate the ends of said side walls and projecting transversely therefrom towards the collapsible section, said last mentioned brackets having large supporting walls rotatable thereon which extend partially beyond the rearmost edge of the rearmost wall of the collapsible section when the collapsible section is collapsed in order to permit the large wheels to also engage the ground surface when the collapsed cabinet is tipped, and means for holding the walls of the collapsible section collapsed during the transporting of the cabinet, said means consisting of detachable pins carried by the last mentioned brackets for abutment at the rearmost surfaces of the rearmost wall of the collapsible section.
14. In a bullet-proof cabinet construction the combination of a rigid section comprising side walls, a top wall, a bottom wall, and a forward wall all integrally and rigidly connected, said rigid section being formed to provide a rearwardly opening pocket, and a collapsible section comprising top and bottom walls hingedly connected to the top and bottom walls of the rigid section and swingable at their free ends inwardly into the pocket of the rigid section, means on the side walls of the rigid section to limit the amplitude of inward swinging of the top and bottom walls of the collapsible section to provide a space between the same and the front wall of the rigid section wherein articles may be received, said collapsible section further including collapsible side walls and a rear wall, and means to retain the walls of said collapsible section collapsed.
